By *Cadrow & Co.* ATTORNEYS

UNITED STATES PATENT OFFICE.

JAMES JOSEPH O'DONNELL, OF PADUCAH, KENTUCKY.

ROTARY PUMP.

No. 870,310.

Specification of Letters Patent.

Patented Nov. 5, 1907.

Application filed July 31, 1906. Serial No. 328,594.

To all whom it may concern.

Be it known that I, JAMES JOSEPH O'DONNELL, a citizen of the United States, residing at Paducah, in the county of McCracken and State of Kentucky, have 5 invented a new and useful Rotary Pump, of which the following is a specification.

This invention relates to motor driven centrifugal pumps designed for pumping out water from barges, vessels, cellars, excavations, and the like, and more particularly to that type constituting the subject-matter of my pending application for Letters Patent, Serial No. 302,276, filed Feb. 21, 1906.

The invention has for one of its objects to improve and simplify the construction and operation of the impeller wheel and associated parts, so as to increase the 15 efficiency of the pump.

A further object of the invention is to arrange the driving shaft within the discharge pipe of the pump, or other suitable casing or sheath, so that the pump 20 can be transported from place to place without danger of the shaft being damaged.

A further advantage in arranging the driving shaft within the discharge pipe is that the water passing through the latter maintains the shaft bearings cool.

25 Another object is the provision of an automatic mechanism for starting and stopping the motor as the water in the barge reaches a predetermined high or low level, so that at no time can the water reach a dangerously high mark.

30 Another object of the invention is to provide a suitable signal device whereby the officer or attendant is made aware of the fact that the level of the water has risen to the maximum point and the motor has started into operation. The attendant, being thus warned, is 35 enabled to keep up a watch to ascertain if the leakage of the boat exceeds the capacity of the pump, whereupon a second pump may be brought into operation. If desired, a plurality of automatically started pumps may be employed, their arrangement being such that 40 they will operate successively as the leakage exceeds the delivery of the pump or pumps then in operation.

With these objects in view, and others, as will appear as the nature of the invention is better understood, the invention comprises various novel features 45 of construction and arrangement of parts, which will be more fully described hereinafter and set forth with particularity in the claims appended hereto.

In the accompanying drawing, which illustrates one of the embodiments of the invention, Figure 1 is a central vertical section of the pump with portions thereof shown in elevation and an intermediate portion broken away. Fig. 2 is a transverse section on line 2-2 of Fig. 1. Fig. 3 is a side elevation of a pump slightly modified in construction and provided with the auto-

matic mechanism for starting and stopping the motor 55 thereof. Fig. 4 is an enlarged detail view of the switch for controlling the motor.

Corresponding parts in the several figures are indicated throughout by similar characters of reference.

Referring to the drawing, 1 designates the casing of 60 the pump having an inlet opening at its lower end covered by a strainer 2, and an outlet opening 3 at its upper end communicating with the discharge pipe 4. Within the casing 1 is arranged an impeller wheel comprising horizontal top and bottom heads 5 and 6 and 65 radially extending vanes 7 rigidly connected at their ends to the heads. The lower head 6 is provided with a central inlet opening 8 around which is a cylindrical boss 9 which engages and cooperates with the bearing plate 10 to form a step bearing. The boss 9 is shouldered and reduced so as to engage in the opening 11 of the plate 10, and the said plate is secured to the casing by bolts 12. Arranged around the impeller wheel are 70 stationary vanes 13 extending with their lengths parallel to the vanes 7 of the wheel. These vanes 13 are 75 spaced apart in a circle around the wheel and are shaped with their portions adjacent the wheel in tangential relation to the latter, while the outer portions thereof curve in a general radial direction, their function being to reduce the rotary motion of the water im- 80 parted to it by the wheel, so that the water will rise more readily in the chamber 14 around and above the vanes 13 and pass to the discharge pipe 4 with less internal friction. The vanes 13 may be formed integral with, or be otherwise secured to, the casing 1. 85

The upper ends of the vanes 13 are connected with a horizontally extending head 15, so that a cage-like structure is provided around the impeller wheel. The head 15 is provided with a central bearing 16 for the driving shaft 17 to which the impeller wheel is rigidly 90 secured. In a portable pump it is preferable to arrange the driving shaft within the discharge pipe 4, so that the pump can be transported without the shaft being subject to injury. For this purpose, the discharge pipe is provided with suitable bearings, one 95

being indicated at 18, for receiving the driving shafts. These bearings may be arranged to dispose the shaft in concentric or eccentric relation to the discharge pipe, as desired. At the upper end of the discharge pipe where the latter bends to form the spout 19, is arranged an electric motor 20 whose shaft aligns with the driving shaft 17 and is directly connected therewith. The motor 20, may be of any desired construction, and is adapted to be connected in circuit with a suitable source of electro motive force by flexible connections, 100 indicated at 21, so that the pump may be moved from place to place. At the mouth of the spout 19 is provided a valve 22 which is arranged to be normally 105

closed when the pump is idle and to be opened by the discharge of water from the impeller wheel. Adjacent the valve is a suitable signal device that is adapted to be sounded upon the opening of the valve, so that the attendant will be informed when the pump begins to discharge. Any suitable audible signal may be provided for this purpose, such, for instance, as a gong 23 mounted on the spout, and a clapper 24 connected with the valve, so that as the latter opens it will strike 10 the gong. Such a signal device is of most particular value in connection with an automatic means for starting and stopping the motor, such as will be described hereinafter in reference to Fig. 3.

In operation, the motor rotates the impeller wheel 15 as soon as the circuit is closed. Water is thus drawn into the pump by the impeller wheel through the strainer 2 and inlet opening 8 and from the center of the propeller wheel is discharged tangentially in a horizontal plane by the vanes 7. The stationary 20 vanes 13 receive the tangentially discharged water and arrest its tangential motion so that it will discharge upwardly through the chamber 14 and discharge pipe 4. In passing up through the discharge pipe, the shaft bearings are kept cool, so that a comparatively high 25 rotative speed may be employed.

In the modified form of pump shown in Fig. 3, the structural features are substantially the same as those already described, except that the power shaft 17 is arranged exterior to the discharge pipe 25 and is 30 closed in a sheath 26 secured to the pipe 25, thereby amply protecting the shaft from injury. In this construction, the discharge pipe 25 is arranged with its axis slightly eccentric to the axis of the casing 1, and, furthermore, the upper part of the discharge pipe is 35 offset at 27 so as to support the motor 20 in proper operative relation to the driving shaft 17.

The mechanism for automatically stopping and starting the motor, which may be used with either form of pump, comprises a float 28, preferably in the form of a 40 ring arranged around the discharge pipe so as to be guided thereby, a vertically extending rod 29, and a switch 30 at the upper end thereof for opening and closing the motor circuit. In Fig. 3, the switch is 45 enclosed in a casing 31 arranged on or adjacent the motor base. As shown in Fig. 4, the tongue 32 of the switch is provided with an apertured arm 33 through the aperture 34 of which the rod 29 loosely extends. Bearing on opposite sides of the arm 33, and arranged around the rod 29, are helical compression springs 35. These 50 springs are held under compression by nuts 36 forming abutments for the ends of the springs opposite from the arm 33. By means of these springs, the blade 32 can be quickly connected or disconnected with respect to the spring contacts 37, so that sparking will be reduced 55 to a minimum during the opening and closing of the switch. That is to say, as the float 28 moves upwardly by virtue of a rise in level of the water in which the lower end of the pump is submerged, the lower spring 35 will be compressed gradually until such a point is reached that 60 the switch will be snapped closed. The pump will thus be started into operation and the seep water in the barge or vessel will be pumped out. As the float lowers,

the upper spring 35 will be compressed until a certain point is reached, sufficient to snap the switch open. In order to enable the switch to be opened and closed 65 suddenly, by virtue of the compression of the springs, a stop device is provided which yieldingly holds the switch in either open or closed position during the time the float is moving from one extreme position to the other. This stop device comprises a leaf spring 38 70 secured to the insulating base 39 of the switch, and a segmental finger or projection 40 on the tongue 32 of the switch. The free end of the spring 38 is provided with a tooth 41 which is adapted to engage in one or the other of two spaced notches 42 on the member 40. 75 When the tooth engages one notch, the switch is closed, and when it engages the other notch, the switch is open. The tooth and notches are so shaped as to yieldingly hold the switch open or closed, so that the tooth will be automatically released from the notch that it engages 80 when the compression of one or the other of the springs 35 exceeds the gripping effect of the stop device. The leads of the electric circuit are designated by 43 and 44 by means of which current is supplied to the motor. On one of these leads may be provided, if desired, a 85 suitable signal device, such as a bell 45 of the electro-magnetically operated type, so as to be sounded as soon as the motor circuit is completed by the movement of the float, and thereby warn the attendant of the condition of the seep water in the barge or vessel. This 90 alarm may be preferably arranged in shunt relation to the lead 44 and be provided with a hand operated switch 46, so as to be cut into or out of circuit, as desired.

With a pump equipped with the automatic controlling mechanism, the height of the seep water in a vessel or 95 barge can be effectively kept within safe limits, since when the level of the water reaches a certain height, the pump will be automatically started and the water pumped out until a minimum low level is reached, whereupon the pump will cease operating. In the case 100 of an empty barge, it is usually desirable to have a certain minimum amount of water retained therein, so as to prevent the heat of the sun from opening the cracks. It will be noted that the float does not fall to the lowest point of the pump, so that the motor will be stopped 105 before the barge is pumped completely dry. In order, however, to pump the barge dry, so as to permit the same to be loaded with merchandise, provision is necessary for operating the motor independently of the float controlled starting and stopping mechanism. For this 110 purpose, a circuit 47 shunting the switch 30 is provided, the same having a manually controlled switch 48 whereby the shunt can be opened and closed. Thus, when it is desired to completely pump out the seep water, the switch 48 is closed, so that the motor will operate 115 independently of the automatically operated switch 30.

In some cases it will be desirable to employ several automatically actuated pumps, so that when the leakage should exceed the capacity of one pump, another, or more, pumps would be automatically called into 120 service and thereby possibly preventing a ship from filling up and sinking. With such an arrangement, it would be preferable to have the floats of the several pumps so arranged that the pumps would be called

into action one after another as the level of the water would rise.

What is claimed is:—

The combination of a pump, an electric motor for driving the same, an automatically actuated mechanism for opening and closing the circuit of the motor, a signal device connected in circuit with the motor, and a manually controlled device for controlling the motor independently of the said mechanism.

In testimony that I claim the foregoing as my own, I 10 have hereto affixed my signature in the presence of two witnesses.

JAMES JOSEPH O'DONNELL.
